CLAIM

The ornamental design for a water drone, as shown and described.

DESCRIPTION

FIG. 1 is an upper prospective view of a water drone showing my new design;

FIG. 2 is a lower prospective view thereof;

FIG. 3 is a front view thereof;

FIG. 4 is a near view thereof;

FIG. 5 is a left side view thereof;

FIG. 6 is a right side view thereof;

FIG. 7 is a top view thereof; and,

FIG. 8 is a bottom view thereof.

In the drawings, the broken lines depict portions of the water drone that form no part of the claimed design.
